Primary Examiner — Cynthia M. Chin*(74) Attorney, Agent, or Firm* — Plumsea Law Group, LLC(57) **CLAIM**

The ornamental design for a construction set element, as shown and described.

DESCRIPTION

FIG. 1 is a top isometric perspective view of a construction set element showing the new design;

FIG. 2 is a front elevational view of the construction set element of FIG. 1;

FIG. 3 is a rear elevational view of the construction set element of FIG. 1;

FIG. 4 is a left side elevational view of the construction set element of FIG. 1;

FIG. 5 is a right side elevational view of the construction set element of FIG. 1;

FIG. 6 is a top plan view of the construction set element of FIG. 1; and,

FIG. 7 is a bottom plan view of the construction set element of FIG. 1.

The evenly spaced broken lines and unshaded areas represent portions of the article's appearance that form no part of the claimed design.

1 Claim, 7 Drawing Sheets(56)
